UNITED STATES PATENT OFFICE.

WILLIAM RABKIN, OF NEW YORK, N. Y.

DESIGN FOR A PICTURE-MACHINE CASING.

Application filed August 19, 1927. Serial No. 23,146. Term of patent 14 years.

To all whom it may concern:

Be it known that I, WILLIAM RABKIN, a citizen of the United States, and a resident of the city of New York, borough of Manhattan, in the county of New York and State of New York, have invented a new, original, and ornamental Design for Picture-Machine Casings, of which the following is a specification, reference being had to the accompanying drawings, forming part thereof.

The figure is a perspective view of a picture machine casing, showing my new design.

I claim:

The ornamental design for a picture machine casing, as shown.

Signed at New York in the county of New York, and State of New York this 17th day of August, A. D. 1927.

WILLIAM RABKIN.
